James A. Atherton Inventor

United States Patent Office.

JAMES A. SUTHERLAND, OF ELMWOOD, ILLINOIS.

Letters Patent No. 82,361, dated September 22, 1868.

IMPROVED HORSE-COLLAR.

The Schedule referred to in these Letters Patent and making part of the same.

Be it known that I, JAMES A. SUTHERLAND, of Elmwood, in the county of Peoria, and State of Illinois, have invented a new and improved Horse-Collar; and I do hereby declare the following is a full and exact description thereof, reference being had to the accompanying drawings, and to the letters of reference marked thereon.

Figure 1 is a perspective view.

Figure 2 is a side view.

Figure 3 is a front view.

Figure 4 is a representation of the hook for the tug or trace.

Figure 5 is a view of the strap or fastening of the collar.

This horse-collar is made of wood, formed and curved into the shape represented in the drawings, and fitted to the neck and shoulders of the horse. It is constructed in two sections or parts, the upper section, A A, being so formed as to rest upon the withers of the horse, and extend down upon either side even with the breast. The lower section, B, is made in form to fit to the breast of the horse, and of such length as to join the ends of the same to the ends of the upper section.

The two sections are united upon one side by means of iron straps, g, riveted to the outer side of the upper section, and C riveted to the lower section, and connected by the hinge-joint m.

The strap C is extended round the outer side of the lower section, and prolonged sufficiently to afford means of fastening the same to the side of the upper section opposite to the joint m.

The end of the strap C, extended beyond the section B, is provided with holes, for the reception of the loop e and peg, and the hook d fitted to the loop e.

In the lower ends of the upper sections are recesses, a a, for the reception of the pins b b, which hold the two sections in position, and strengthen the connection. The rings k for the leading-lines, rings i i for the connection of the neck-yoke, hook h for connection of the traces or tugs, and other hooks and rings, are attached to the collar in such positions as each case may require.

This collar is used without hames, the collar itself supplying the place of the same, by having the various parts of the harness, usually connected with the hames, joined to the collar.

Claim.

What I claim as my invention, and desire to secure by Letters Patent, is—

A horse-collar, made of wood, when constructed substantially as above described.

JAMES A. SUTHERLAND.
